Primary Examiner — Stacia Cadmus*(74) Attorney, Agent, or Firm* — Jansson Munger McKinley & Shape Ltd.(57) **CLAIM**

The ornamental design for an aerodynamic wheel cover, as shown and described.

DESCRIPTION

FIG. 1 is a front perspective view of the aerodynamic wheel cover;

FIG. 2 is a rear perspective view of the aerodynamic wheel cover of FIG. 1;

FIG. 3 is a front plan view of the aerodynamic wheel cover of FIG. 1;

FIG. 4 is a rear view of the aerodynamic wheel cover of FIG. 1;

FIG. 5 is a top elevation view of the aerodynamic wheel cover of FIG. 1;

FIG. 6 is a bottom elevation view of the aerodynamic wheel cover of FIG. 1;

FIG. 7 is a left-side elevation view of the aerodynamic wheel cover of FIG. 1; and,

FIG. 8 is a right-side elevation view of the aerodynamic wheel cover of FIG. 1.
